UNITED STATES PATENT OFFICE.

WILLIAM F. STRAND, OF DES MOINES, IOWA.

IGNITION SYSTEM FOR INTERNAL-COMBUSTION ENGINES.

1,336,933.

Specification of Letters Patent. Patented Apr. 13, 1920.

Application filed March 18, 1919. Serial No. 283,403.

To all whom it may concern:

Be it known that I, WILLIAM F. STRAND, a citizen of the United States, and resident of Des Moines, in the county of Polk and 5 State of Iowa, have invented a certain new and useful Ignition System for Internal-Combustion Engines, of which the following is a specification.

The object of my invention is to provide 10 an ignition system for internal combustion engines, of simple, durable and inexpensive construction.

More particularly it is my object to provide a device for normally opening the low 15 tension circuit of a timing device except at the instant that the high tension circuit is closed through the spark plugs of the engine.

A further object of my invention is to 20 provide means whereby the closing of the low tension circuit may be accomplished by a cam attached to the shaft which carries the circuit closing device for the high tension circuit.

25 With these and other objects in view, my invention consists in the construction, arrangement and combination of the various parts of the device, whereby the objects contemplated are attained, as hereinafter more 30 fully set forth, pointed out in my claims, and illustrated in the accompanying drawings, in which:

Figure 1 shows a plan view of my improved device, with the upper half of the 35 casing removed.

Fig. 2 shows a central, vertical, sectional view, taken on the line 2-2 of Fig. 1.

Fig. 3 shows a detail view of a part of my invention; and

40 Fig. 4 shows a detail of another part of my invention.

Referring to the accompanying drawings, I have used the reference numeral 10 to indicate half of the casing for my timing 45 device, and the reference numeral 11 to indicate the other half, which is similarly shaped and secured thereto by means of screws 12. The portion 10 of the casing has a bearing member 13 disposed centrally 50 thereof, and designed to receive the shaft 14, which may be an extension of the cam shaft of the motor or connected therewith to revolve at the proper speed.

The shaft 14 is rotatably but nonslidably mounted in the bearing 13 by means of an 55 annular flange 15 which is received within the casing, and a collar 16 which may be secured in place on the shaft outside the casing as by means of screws 17.

Adjacent to the flange 15 the shaft 14 has 60 an in-turned shoulder 18, having a roughened face. Extending from the shoulder 18 the shaft is contracted at 19 and again contracted at 20, the latter portion being externally screw-threaded. 65

Received on the contracted portion 19 is a cam 21 provided with points 22 which equal in number the number of cylinders which the engine has to which the timer is attached. The cam 21 is provided with a 70 roughened surface or face designed to contact with the roughened surface of the shoulder 18.

A washer 23 has a screw-threaded opening 75 therein, designed to coat with the threads on the contracted portion 20 and to hold the cam 21 against the shoulder 18. It will thus be seen that by means of the roughened surfaces on the cam 21 and the shoulder 18 and the washer 23, the cam 21 may be locked 80 in any position relative to the shaft 14.

A contact arm 24 extends laterally from the end of the shaft 14 and is secured thereto by means of a vertical portion 25 having an internally screw-threaded opening there- 85 in designed to coat with the threads on the contracted portion 20. The arm 24 is composed of non-conducting material and is provided on its upper surface with a strip of 90 conducting material 26, and contact points 27 and 28 are disposed at the ends of the strip 26.

Binding posts 29 are secured in the casing member 11 in position spaced from each other and in position to coat with the contact 95 27 to close the high tension circuit through the spark plugs of the engine. The contact 28 is connected with the secondary circuit of the coil of the ignition circuit by means of the binding post 30. 100

It will thus be seen that the revolution of the arm 24 will successively place the contact 27 in position to close the circuit through the binding posts 29. In the form of the device shown, the contact 27 is moved to 105 position approximately one-thirty-second of

an inch from the contact points 31 at the base of the binding post 29, so that the circuit is closed by means of a spark which jumps across between the contacts 27 and 31.

5 A support 32 is mounted in the casing member 10 and carries a flat spring 33 which projects to position to coact with the points 22 on the cam 21. A stop bracket 34 is also secured to the support 32, and normally 10 bears against the spring 33 at a place intermediate of the ends of the spring.

Adjacent to the support 32 a binding post 35 is secured to the casing 10 and extends therethrough. Washers 36 or other 15 suitable means are provided to insulate the binding post 35 from the casing 10. The binding post 35 is provided with a slideable contacting member 37 which may be secured from movement by means of a tight- 20 ening screw 38. In the form shown, the binding post is split down part way adjacent to the opening which receives the slideable contact 37, so the tightening of the screw 38 tightens together the split por- 25 tions of the binding post, thereby frictionally engaging the sliding member 37.

Means are provided for adjusting the relative position of the spring 33, comprising slots 39 which receive the screws 40, so 30 that by loosening the screws 40 the spring 33 may be moved longitudinally.

The binding post 35 is connected by any suitable means, as by a wire 41, with the source of low tension electrical energy.

35 In the practical operation of my improved device the parts are installed as shown in Figs. 1 and 2 of the drawing, in position where the shaft 14 may be connected with the engine to so rotate the 40 shaft that the contact 27 will successively close a circuit through the contacts 31 at the proper time to fire the explosive charges in the cylinders. The cam 21 is then adjusted to such position relative to 45 the spring 33 that the points 22 will successively contact with the spring to bend the spring on the stop 34 just prior to the time that the contacts 27 and 31 are adjacent to each other. As the points 22 revolve 50 they first flex the spring 33 and then release it, whereby the spring 33 rebounds to position where it contacts with the sliding contact member 37.

The adjustment of the positions of the 55 cam 21, the spring 33 and the sliding contact member 37 must be such that the rebound of the spring 33 will occur at the instant that the spark should pass between the contact 27 and the adjacent contact 31.

60 From the foregoing it will be seen that the low tension circuit of the ignition system for the engine will be open at all times except at the instant when the spark in the cylinders should occur.

65 The advantages of this arrangement which

I have termed auto-mechanical will be obvious from the foregoing description of its operation.

Some changes may be made in the details of the structure and arrangement of my device, without departing from the essential purpose of my invention, and it is my intention to cover by my claims any modified forms of structure or use of mechanical equivalents which may be reasonably included within their scope.

I claim as my invention:

1. In a multiple cylinder internal combustion engine ignition system comprising a low tension circuit, a high tension circuit, 80 and means for successively closing the high tension circuit through each of a plurality of contacts connected with the ignition devices of the respective cylinders, a support, a stop bracket secured thereto, an elongated flat resilient conductor having one end secured to the support and adapted to normally yieldingly bear against the stop intermediate of the ends of the conductor, a contact secured to the conductor between 85 the free end thereof and the stop, a second contact secured to the support in position spaced from the first contact, means for adjusting the distance of the second contact from the first, and means operated by the 90 first described means for flexing the conductor against the stop somewhat prior to the closing of the circuit through each of the first described contacts, whereby the rebound of the conductor will bring the two 95 last described contacts together for an instant.

2. In a multiple cylinder internal combustion engine ignition system comprising a low tension circuit, a high tension circuit, 105 and means for successively closing the high tension circuit through each of a plurality of contacts connected with the ignition devices of the respective cylinders, a support, a stop bracket secured thereto, an elongated flat resilient conductor having one end secured to the support and adapted to normally yieldingly bear against the stop intermediate of the ends of the conductor, a contact secured to the conductor between 110 the free end thereof and the stop, a second contact secured to the support in position spaced from the first contact, and means for flexing the conductor against the stop somewhat prior to the closing of the circuit through each of the first described contacts, whereby the rebound of the conductor will bring the two last described contacts 115 together for an instant.

3. In a device designed to automatically 125 break the low tension circuit of an electrical ignition system of an internal combustion engine having low and high tension circuits, an elongated flat resilient device having one end fixed and adapted to normally yield- 130

ingly press against a stop, a stop disposed intermediate of the ends of said resilient device, a contact spaced from said device and disposed on the side thereof opposite said stop, and means for flexing said spring on the stop prior to the closing of the high tension circuit and for releasing said spring

at the instant that the high tension circuit is closed, whereby the spring may rebound against said contact to thereby simultaneously close the low tension circuit. 10

Des Moines, Iowa, March 8, 1919.

WILLIAM F. STRAND.
